(57) **CLAIM**

The ornamental design for a conveyor belt, as shown and described.

DESCRIPTION

FIG. 1 is a top view showing our new design for a conveyor belt,

FIG. 2 is a left side view thereof,

FIG. 3 is a front view thereof,

FIG. 4 is a cross-sectional view taken along the line 4-4 on FIG. 3,

FIG. 5 is an enlarged front view of a rib,

FIG. 6 is an enlarged front view of middle ribs,

FIG. 7 is an enlarged side view of a lower end of a side rib,

FIG. 8 is an enlarged side view of an upper end of a side rib,

FIG. 9 is an enlarged cross-sectional view of middle ribs taken along the line 9-9 on FIG. 6,

FIG. 10 is an enlarged cross-sectional view of a rib taken along the line 10-10 on FIG. 5,

FIG. 11 is a top view showing our new design for a conveyor belt,

FIG. 12 is a left side view thereof,

FIG. 13 is a front view thereof,

FIG. 14 is a cross-sectional view taken along the line 14-14 on FIG. 13,

FIG. 15 is an enlarged front view of a rib,

FIG. 16 is an enlarged front view of middle ribs,

FIG. 17 is an enlarged side view of a lower end of a side rib,

FIG. 18 is an enlarged side view of an upper end of a side rib,

FIG. 19 is an enlarged cross-sectional view of middle ribs taken along the line 19-19 on FIG. 16; and,

FIG. 20 is an enlarged cross-sectional view of a rib taken along the line 20-20 on FIG. 15.

1 Claim, 20 Drawing Sheets

Related U.S. Application Data

having an international filing date of Feb. 22, 2016,
now Pat. No. Des. 812,335.
